UNITED STATES PATENT OFFICE.

JOHN J. WALSH, OF YONKERS, NEW YORK, ASSIGNOR TO YONKERS SPECIALTY COMPANY, OF YONKERS, NEW YORK, A FIRM.

WIRES-CONNECTOR.

No. 875,872.

Specification of Letters Patent.

Patented Jan. 7, 1908.

Application filed April 10, 1905. Serial No. 254,900.

To all whom it may concern:

Be it known that I, JOHN J. WALSH, a citizen of the United States, residing at Yonkers, in the county of Westchester, State of New York, have invented certain new and useful Improvements in Wire-Connectors, of which the following is a specification, reference being had to the drawing accompanying and forming a part of the same.

10 My invention relates to devices for connecting electric conductors, such as telephone and telegraph wires, and has for its object to provide a device of this kind which shall be simple, inexpensive to manufacture, 15 and at the same time highly effective for the purpose intended.

To these ends the invention consists in novel features and combinations of parts hereinafter described, and more particularly 20 set forth in the claims.

In the drawings, Figure 1 is a side elevation of the preferred embodiment of the invention showing the same employed to connect two wires. Fig. 2 is a vertical section.

25 Fig. 3 is a plan view of a washer used in the device.

The body of the device consists of a head, *a*, and a hollow shank, *b*. The latter is slotted, as indicated at *c*, the slot extending 30 preferably down to the head *a* and having a concave bottom, as indicated at *d*. The upper part of the shank is internally threaded to receive a binding screw *e*. The screw threaded portion may extend as far down 35 into the shank as desired, depending upon the size of the wire with which the device is to be used. Small wires will require the screw *e* to be set farther into the shank.

In using the device one of the wires is 40 placed in the slot, as indicated by *f*, and upon this is placed a washer of suitable form, as for example that shown in Fig. 3. The washer there illustrated consists of a flat ring, *g*, with a bar *h* arranged diametrically

across the opening therein. The bar is 45 slightly narrower than the slot in the shank *b*, so that it can pass down into the slot and rest on the wire *f*, as shown in Fig. 2. The next wire is now placed upon the washer, as indicated by *i*, and a washer is placed on the 50 wire as in the first case. Other wires may be placed in the device if desired, in the same manner, the number depending on the capacity of the device and the number of wires which it is desired to connect together. The 55 last wire having been covered with a washer, the screw *e* is turned down upon the cross-bar of the same with sufficient firmness to give the desired degree of contact between all the parts. A slight reverse turn of the 60 screw releases the parts and the wires can be at once disengaged.

The device may of course be made in a variety of forms without departing from the spirit of my invention, and I therefore do not 65 consider myself limited to the embodiment herein specifically shown and described.

What I claim is:

1. In a wire connector, the combination of an internally threaded body portion, having 70 a transverse slot to receive the wires, separating members having bars adapted to lie in the slot between the wires, and a screw in the body portion adapted to press the wires and separating members firmly together, as 75 set forth.

2. In a wire connector, the combination of an internally threaded body portion having a transverse slot to receive the wires, separating washers having diametrically arranged cross-bars adapted to lie between the wires in the slot, and a screw in the body portion adapted to press the wires and washers 80 firmly together, as set forth.

JOHN J. WALSH.
